Philip E. Beck

UNITED STATES PATENT OFFICE.

NIXON LEE, OF BROOKLYN, NEW YORK.

SPARK-PLUG.

1,320,013.

Specification of Letters Patent. Patented Oct. 28, 1919.

Application filed January 3, 1919. Serial No. 269,505.

To all whom it may concern:

Be it known that I, NIXON LEE, a citizen of the United States, and a resident of the borough of Brooklyn, in the county of Kings 5 and State of New York, have invented certain new and useful Improvements in Spark-Plugs, of which the following is a specification, reference being made to the accompanying drawings, forming a part 10 thereof.

My invention relates to spark-plugs to be used for explosive engines, and the objects of my invention are, among other things, to form a spark-plug which may be readily 15 taken apart for cleaning or other purposes, the parts of which may also be easily and compactly assembled together with means to effectively seal such component parts under the gaseous pressure of the engine cylinder 20 der, while maintaining the central electrode of the spark-plug in proper alinement. A further object of my invention is to provide a simple, durable and inexpensive spark- 25 plug wherein the gaseous pressure is directly utilized to more closely pack the several parts comprising the spark plug structure so as to prevent leakage, thereby furnishing an effective seal about the central core held in operative position within the 30 spark-plug body proper.

With the above and other objects in view, my invention comprises the novel construction, combination and arrangement of parts to be hereinafter specifically described and 35 set forth in the appended claims.

I attain these advantageous results by the spark-plug shown in the accompanying drawings in which—

Figure 1 is a vertical sectional view of a 40 preferred embodiment of my invention shown partly in elevation;

Fig. 2 is an enlarged sectional plan view taken on the line 2—2 in Fig. 1;

Fig. 3 is an enlarged vertical sectional 45 view of the annular tapered bushing;

Fig. 4 is a top plan view of the bushing shown in Fig. 3; and

Fig. 5 is a diagrammatic vertical sectional view showing the tapered bushing 50 surrounding the central core within the depending screw-threaded flange of the nut which secures the core within the body portion of the plug, the annular beading carried on the lower rim of the nut flange for holding the tapered bushing in position, be-

ing shown as it appears before such beading is spun over as shown in Fig. 1.

Similar numerals refer to similar parts throughout the several figures.

Referring to Fig. 1, the spark-plug body 6 or shell 6 is screw threaded at 7 by which it is mounted on the cylinder (not shown) of any explosive engine. The upper portion of the body 6 is formed with a hollow bore 8 screw-threaded at 9 with which the nut 10 with its screw-threaded flange 11 coacts to secure the central insulated core 12 in position. The upper middle portion 13 of the core 12 is in the form of a truncated cone the surface of which is adapted to fit within the inclined annular bore, or shoulder 14 formed in the top of the nut 10, the angles of inclination of the core portion 13 and the shoulder 14 being the same to afford a close fit when the nut 10, having the core 12 depending within the flange 11, is screwed down on the washer 15 of the spark-plug body 6 as shown in Fig. 1.

Within the flange 11 of the nut 10 and surrounding the central core 12, which is somewhat tapered downwardly as shown in Figs. 1 and 5, is placed the annular tapered bushing 16, preferably formed as shown in Figs. 3 and 4; the thin top edge 17 of the bushing 16 extends upwardly into the annular pocket 18, which is V-shaped in vertical elevation, formed between the core 12 and the flange 11 as shown in Figs. 1 and 5. The lower rim of the flange 11 carries the annular beading 19 (shown in Fig. 5) which is adapted to be spun over to hold loosely the bushing 16 in place within the pocket 18 after the bushing 16 has been slipped on the core 12 within the flange 11, yet such beading 19 should not touch the outer surface of the core 12 as shown in Fig. 1, a narrow annular slot being left therebetween.

The central core 12 is made of porcelain, mica or other insulating material, and carries the central electrode 20 mounted centrally within the core 12, such electrode 20 being arranged to protrude equidistantly between a pair of electrodes 21 carried by the spark-plug body 6 in forming a suitable gap for the electric spark. The spark is formed in the well known manner by the jumping of the current from one electrode to another thereby firing the charge in the engine cylinder.

The upper end 22 of the electrode 20 is screw-threaded as shown in Fig. 1 and carries the binding nut 23 by which a wire or electric conduit may be connected. To the 5 top of the core 12 I have fastened the nut 24 and screwed same down on the screw-threaded end 22 of the electrode 20; over the nut 24 I have placed the cap 25 which is adapted to be fitted over and screwed 10 down on the nut 24 to prevent the latter from rotating within the cap 25 and from loosening upon the end 22, owing to the slight eccentricities existing in the base of the nut 24 and the bore of the cap 25. By 15 this means a tight fit is afforded for the wire connections within the binding nut 23.

The operation of my improved spark-plug is substantially as follows: When the parts are in position as shown in Fig. 1, there is 20 a close fit extending between the conical surface 13 of the core 12 and the inclined shoulder 14 of the nut 10 which is maintained by the nut 10 being screwed down within the body 6 as shown in Fig. 1. However I also utilize the pressure of the engine 25 cylinder to force upwardly and maintain in wedged position the tapered bushing 16 within the pocket 18, such gaseous pressure acting uniformly along the entire base of the bushing through the annular slot extending around the core 12 inside the beading 19 as shown in Fig. 1. By this construction the bushing is not only pushed upwardly in the pocket 18 which is located 30 just below the coacting surfaces 13 and 14 of the core 12 and nut 10 respectively to completely seal the union of the core and nut, but such bushing, acting like a wedge on all sides, also tends to hold the electrode 35 20 in proper alignment between the electrodes 21 which is of considerable importance in preventing and reducing the carbon deposits on such electrodes.

It is manifest that my spark-plug may be 40 readily taken apart and assembled again in operative position, and that I have provided a spark-plug construction which embodies in itself great simplicity in structure while affording a double seal against leakages between central insulating core and the nut 45 which secures same in position to the spark-plug body. It will be understood that the spark-plug herein shown and described may be variously modified and changed without departing from the principle and scope of 50 my invention, and that the principle as herein disclosed is applicable to spark plugs in positions other than that of being upright relatively to the engine cylinder walls.

60 I claim as my invention:—

1. A spark plug for explosive engines comprising a body attached to the engine cylinder, an insulated core centrally disposed within said body, separate means to secure 65 said core to said body, and an annular

tapered bushing permanently interposed between the core and securing means and maintained in wedging position therebetween by the pressure from the engine cylinder to seal the core to said securing means.

2. A spark plug for explosive engines comprising a body attached to the engine cylinder, an insulated core centrally disposed within said body, separate means to secure 70 said core to said body, and an annular tapered bushing loosely but permanently interposed between the core and securing means and maintained in wedging position therebetween by the pressure from the engine cylinder to seal the core to said securing 75 means.

3. A spark plug for explosive engines comprising a hollow body attached to the engine cylinder, an insulated core centrally disposed within said hollow body, a nut having 80 a depending annular flange surrounding said core to secure the latter to said hollow body, the lower rim of the flange having an inwardly extending beading, and an annular bushing held within said flange about said 85 core above the beading and maintained in wedging position therebetween by the pressure from the engine cylinder to seal the core and the nut against leakage.

4. A spark plug for explosive engines 90 comprising a hollow body attached to the engine cylinder, an insulated core centrally disposed within said hollow body, a nut having a depending annular flange surrounding 95 said core to secure the latter to said hollow body, the lower rim of the flange having an inwardly extending beading, and an annular tapered bushing held within said flange about 100 said core above the beading and maintained in wedging position therebetween by the pressure from the engine cylinder to seal the core and the nut against leakage.

5. A spark plug for explosive engines comprising a hollow body attached to the engine cylinder, an insulated core centrally disposed within said hollow body, a nut having a depending annular flange surrounding 110 said core to secure the latter to said hollow body, the lower rim of the flange having an inwardly extending beading, and an annular tapered bushing loosely held within said flange about 115 said core above the beading and maintained in wedging position therebetween by the pressure from the engine cylinder to seal the core and the nut against 120 leakage.

6. A spark plug for explosive engines comprising a hollow body attached to the engine cylinder, a tapered insulated core centrally disposed within said hollow body, a nut surrounding said core and having a depending annular flange forming an annular pocket, V-shaped in cross-section, between said flange and said core, the lower rim of the flange having an inwardly ex- 125 130

tending beading, and an annular tapered bushing loosely held within said pocket by said flange and maintainable in wedged position between said flange and core above the 5 beading by the pressure from the engine cylinder to seal the core and nut against leakage.

7. A spark plug for explosive engines comprising a hollow body attached to the 10 engine cylinder, an insulated core centrally disposed within said hollow body, a hollow screw nut coacting with said body and surrounding said core to secure the latter to said hollow body, said nut having a depending 15 annular flange partially surrounding said core, the lower rim of the flange being formed with an inwardly extending beading leaving an annular opening between said beading and said core, and an annular bush- 20 ing permanently held within said flange about said core above said annular opening and maintained in wedging position between

the flange and core by the pressure from the engine cylinder to seal the core and nut against leakage.

25

8. A spark plug for explosive engines comprising a hollow body attached to the engine cylinder, an insulated core centrally disposed within said hollow body, a hollow screw nut coacting with said body and surrounding said core to secure the latter to said hollow body, said nut having a depending 30 annular flange partially surrounding said core, the lower rim of the flange being formed with an inwardly extending beading 35 leaving an annular opening between said beading and said core, and an annular tapered bushing permanently held within said flange about said core above said annular opening and maintained in wedging 40 position between the flange and core by the pressure from the engine cylinder to seal the core and nut against leakage.

NIXON LEE.
